United States Patent

Des. 236,379
Patented Aug. 19, 1975

236,379

DUPLICATING MACHINE

Daniel N. Yanofsky, Jericho, N.Y., assignor to
Pitney-Bowes, Inc., Stamford, Conn.

Filed Dec. 3, 1973, Ser. No. 421,151

Term of patent 14 years

Int. Cl. D16—03

U.S. Cl. D61—1 Q

FIG. 5

FIG. 6

FIG. 2

FIG. 3

FIG. 4

FIG. 1 is a perspective view of a duplicating machine showing my new design;

FIG. 2 is a front elevational view thereof;

FIG. 3 is a rear elevational view thereof;

FIG. 4 is a top plan view thereof;

FIG. 5 is a left side elevational view thereof; and

FIG. 6 is a right side elevational view thereof.

I claim:

The ornamental design for a duplicating machine, as shown.
